CLAIM

The ornamental design for a yagi-uda antenna with triangle loop, as shown and described.

DESCRIPTION

FIG. 1 is a top front perspective view of a yagi-uda antenna with triangle loop;

FIG. 2 is a top front perspective view thereof;
 FIG. 3 is an enhanced view of an attachment point for a triangular member generally along line FIG. 3 in FIG. 2;
 FIG. 4 is a top view thereof;
 FIG. 5 is a front view thereof;
 FIG. 6 is a left side view thereof;
 FIG. 7 is a back view thereof;
 FIG. 8 is a top perspective view of an alternative embodiment of the yagi-uda antenna with triangle loop;
 FIG. 9 is a top perspective view of an alternative embodiment thereof;
 FIG. 10 is an enhanced view of an attachment point for a triangular member on an alternative embodiment generally along line FIG. 10 in FIG. 9;
 FIG. 11 is a top of an alternative embodiment thereof;
 FIG. 12 is a front view of an alternative embodiment thereof;
 FIG. 13 is a right side view of an alternative embodiment thereof;
 FIG. 14 is a back view of an alternative embodiment thereof;
 FIG. 15 is a top perspective view of an alternative embodiment of the yagi-uda antenna with triangle loop;
 FIG. 16 is a top perspective view of an alternative embodiment thereof;
 FIG. 17 is an enhanced view of an attachment point for a triangular member on an alternative embodiment generally along line FIG. 17 in FIG. 16;
 FIG. 18 is a top of an alternative embodiment thereof;
 FIG. 19 is a front view of an alternative embodiment thereof;
 FIG. 20 is a right side view of an alternative embodiment thereof;
 FIG. 21 is a back view of an alternative embodiment thereof;
 FIG. 22 is a top perspective view of an alternative embodiment of the yagi-uda antenna with triangle loop;
 FIG. 23 is a top of an alternative embodiment thereof;
 FIG. 24 is a back view of an alternative embodiment thereof;
 FIG. 25 is a left side view of an alternative embodiment thereof;
 FIG. 26 is a front view of an alternative embodiment thereof;
 FIG. 27 is a top perspective view of an alternative embodiment of the yagi-uda antenna with triangle loop;
 FIG. 28 is a top of an alternative embodiment thereof;
 FIG. 29 is a back view of an alternative embodiment thereof;
 FIG. 30 is a left side view of an alternative embodiment thereof; and,
 FIG. 31 is a front view of an alternative embodiment thereof.
 The broken lines in the drawings form no part of the claimed design.
